UNITED STATES PATENT OFFICE

LAWRENCE H. MCCOLLUM, OF HEALDSBURG, CALIFORNIA

WELL-DRILLING RIG

Application filed December 2, 1926. Serial No. 152,175.

This invention relates to a rig or apparatus designed to furnish the power and operate the parts in connection with the drilling of wells.

5 It is aimed to generally improve, simplify and render such a machine comparatively inexpensive and easy to operate and which combines the use of motive power for drilling operations as well as for trucking and transporting drilling machines.

In addition, it is aimed to provide a machine which is center-balanced; one in which minimum time is required to set up the parts necessary for drilling; to provide a machine 15 in which the weight is equally distributed throughout; to conveniently operate the drilling machine; to provide a novel means for raising the derrick from the engine of the rig; to provide a construction in which 20 the derrick is foldable against the remainder thereof as when being transported; to provide a novel spudding attachment permitting the use of extra heavy drilling tools and construction in which the spudding apparatus is 25 so designed as to give all tools the same stroke as delivered at the crank shaft.

Various additional objects and advantages will become apparent or be pointed out in the description following taken in connection 30 with accompanying drawings.

In said drawings:—

Figure 1 is a view of the rig in plan;

Figure 2 is a side elevation thereof;

Figure 3 is a rear elevation thereof;

35 Figure 4 is a side elevation showing the position of the parts when the rig is being transported;

Figure 5 is a side elevation showing the attachment in place as used when drilling at 40 maximum depth; and

Figure 6 is a view showing the main parts of Figure 6 in plan.

Referring specifically to the drawings, a suitable bed or base is provided at 10, being 45 of wood or metal as preferred, and especially having side beams as at 11, and an intermediate beam as at 12. The engine or prime mover from which power is derived is adapted to be supported on the base 10 and to 50 drive a shaft 13 having suitable clutch con-

nexion with the engine and suitably journaled on the frame 10 and which parts may be standard parts of a heavy duty automobile truck chassis. Shaft 13 in fact is part of a reduction gear unit as used on such a 55 truck so that the speed for drilling may be approximately 300 R. P. M.

The parts forming my invention may be removably connected to said chassis. To this end, a belt 15 is trained over pulley 14 which 60 also is in driving contact with pulleys 16 and 17. Pulley 16 is carried by a shaft 18 journaled in suitable bearings 19 on the base 10. A sand reel drum 20 is keyed to shaft 13. 21 is a lever operable to cause the sand reel pulley 16 to frictionally engage or disengage the belt 15 and 22 is a brake associated with said 65 pulley 16.

Pulley 17 is carried by a shaft 23. To this shaft is mounted two friction clutches. The 70 crank 26 is keyed to sleeve of one clutch which operates the spudding apparatus when clutch is engaged.

The sprocket wheel 27 is keyed to sleeve 75 of other clutch which operates the drawing of tools from well when clutch is engaged. A chain 28 passes over sprocket wheel 27 and also over a sprocket wheel 29 which is keyed to a calf reel shaft 30 journaled in suitable bearings 31 on the beams 11 and 12 and carrying a calf reel drum or tool at 32. The levers 24^a for operating clutches 24 cross the sill near the calf reel and then follow the sill to the main sill of the machine frame near sprocket wheel 29 and then to the front 85 of the machine at the operator's command. One end of sand reel shaft 18 is journaled on the frame of the machine the other end is journaled in lever 21 to which is pivoted at 21^a the frame of the machine. At top of lever, 90

21 is a rod 21^b running to the front of machine and disposed at the operator's command. By pulling on the above mentioned rod 21^b brings the friction pulley in contact with the band wheel causing the sand reel to 95 be set in motion. By forcing the rod 21^b back, throws the friction pulley against the stationary back brake which brake is bolted to frame of machine. A suitable mechanism is provided as at A in connection with shaft 100

30 to prevent retrograde movement thereof and accordingly of the parts in gear therewith. To this end, a ratchet wheel 33 may be keyed on the shaft 30 and have a ratchet pawl 34 coact therewith to slip past the same 5 during its proper movement and to arrest the improper movement thereof. A brake band 33^a surrounds wheels 33 and is under appropriate control of lever 33^b and is of the usual automobile type. Said lever 33^b comes 10 directly under the frame of the machine adjacent sprocket wheel 29 with a sharp L-bend and then direct to the front of the machine at the operator's command.

15 The drum for the drilling cable is shown at 35 and is keyed on a shaft 36 journaled in bearings 37 on the beams 11. This drum has a gear wheel 38 rigid therewith or keyed on shaft 36 with which a gear wheel 39 is adapted to mesh. Said gear wheel 39 is slideable on 20 and rotatable with the shaft 30 in order to mesh and demesh with the said gear wheel 38, being adapted to be shifted by any suitable mechanism as generally suggested at 40^a. 25 Also associated with the shaft 36 is a suitable braking mechanism 40, in order to hold such shaft and the drum 35 stationary when desired.

From the frame post 10 posts 41 rise at one 30 end and have a derrick frame 42 connected thereto as by hinges 43 so that said frame may be moved into parallelism with the base 10 while the parts are being transported or moved from place to place and as suggested in Figure 4. Said derrick comprises beams 45 and 46, bolted together at 47 in partly overlapping and offset relation. The parts 35 of the derrick and the posts 41 are preferably outwardly inclined and upwardly diverged. The bars 46 engage the outer surfaces of the posts 41 to generally reinforce the derrick when in drilling or operative position.

40 At the other end of the base 10, posts 48 are provided and when the derrick is erected, brace rods 49 are detachably fastened to the posts 48 and the bars 45, in any suitable manner, as by means of bolts 50. In addition, brace rods 51 may be detachably bolted at 52 to the base 10 and the bar 46.

50 A stationary shaft 53 spans the posts 41 at their top and an idler pulley 54 is journaled thereon. Angle irons 56 are pivotally or loosely mounted at one end on the shaft 53 and at the other end have a shaft 56 rigidly connected thereto and on which a pulley 57 is journaled. Pivotally connected to the shaft 56 is a spudding or drilling pitman 58 which by means of a wrist pin 59 may be adjustably connected to any one of a series of 55 openings 60 in the crank 26.

At the top of beams 45, they are spanned by rods or shafts 61 and 62 on which pulleys 63 and 64 are journaled, respectively. A 60 drilling cable is shown at 65 and passes from

the drum 35 over pulley 54, pulley 57 and pulley 63 to the well hole.

The sand line is shown at 66 and passes from the sand reel drum 30 over the pulley 63 to the well hole.

70 When the device is being transported from place to place, it may be carried in a wagon, on a truck or tractor or otherwise since it occupies minimum space. The derrick may be swung to horizontal position as suggested in Figure 3, with the beam 45 engaging the posts or rests 48 in order to support them. It is to be understood that as the various parts are detachably connected, those interfering with the said operation may be removed prior to the collapsing or folding of the derrick.

75 The derrick from the position of Figure 4 is adapted to be elevated by power from the machine and to this end, a cable 67 is adapted to be connected to the drum 32 on the calf reel shaft 30, which cable passes through and over pulley 68 and 69, respectively carried by the frame 10 and the derrick adjacent the lower end of the latter. As a result of this construction, tensioning of 80 the cable 67 will elevate the derrick.

85 If desired, braces 70 may be detachably bolted as at 71 to the base 10 and the posts or rests 48.

90 In cases where drilling is to be effected at maximum depth, that is between 200 ft. and 800 ft., usually, the attachment illustrated in Figures 5 and 6 is used. This attachment consists of a beam 80 which is detachably connected at 81 to the shaft 53 and 95 journaled on the latter, such beam 80 supplanting the beam or rod 55. One end of the beam 80 in this instance is pivotally connected to the shaft 56 and from the other end of the beam, a temper screw device used in deep drilling, as suggested at 82, is used. This device constitutes no part of the present invention and accordingly is not specifically shown. A truss rod or brace 83 is provided 100 for beam 80, extending from adjacent one end thereof to adjacent the other end thereof.

105 Changes may be resorted to provided they fall within the spirit and scope of the invention.

110 I claim as my invention:—

115 1. A rig of the class described having a base, a rearwardly and upwardly inclined post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, and a crank connection between said pitman and spudding shaft.

120 2. A rig of the class described having a base, a rearwardly and upwardly inclined 125 post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, and a crank connection between said pitman and spudding shaft.

130

post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, said drum and second pulley being on opposite sides of the longitudinal median line of the base, and a crank connection between said pitman and spudding shaft, the parts being arranged so that the rig will be substantially center-balanced.

3. A rig of the class described having a base, a rearwardly and upwardly inclined post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, a crank connection between said pitman and spudding shaft, the parts being arranged so that the rig will be substantially center-balanced, and a connection between the shaft of said first and second mentioned pulleys.

4. A rig of the class described having a base, a rearwardly and upwardly inclined post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, said drum and second pulley being on opposite sides of the longitudinal median line of the base, a crank connection between said pitman and spudding shaft, and a connection between the shaft of said first and second mentioned pulleys, the parts being arranged so that the rig will be substantially center-balanced.

5. A rig of the class described having a base, a rearwardly and upwardly inclined post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, said drum and second pulley being on opposite sides of the longitudinal median line of the base, a crank connection between said pitman and spudding shaft, the parts being arranged so that the rig will be

substantially center-balanced, and interchangeable connections between said pulleys according to the depth of drilling.

6. A rig of the class described having a base, a rearwardly and upwardly inclined post thereon, a shaft supported by said post, a derrick pivoted to said post and capable of folding movement relative to the base, a pulley on said shaft, a drum on the base, a drilling cable passing from said drum over said pulley, a second pulley over which said drilling cable passes, a spudding shaft on the base, means to drive said spudding shaft comprising a pitman connected with the second pulley, said drum and second pulley being on opposite sides of the longitudinal median line of the base, a crank connection between said pitman and spudding shaft, the parts being arranged so that the rig will be substantially center-balanced, and a beam pivoted to the shaft of said pulleys, and a tool carried by said beam.

In testimony whereof I affix my signature.

LAWRENCE H. McCOLLUM.
